UNITED STATES PATENT OFFICE

KARL FASSNACHT, OF PROVIDENCE, RHODE ISLAND, ASSIGNOR TO SPEIDEL CORPORATION, A CORPORATION OF RHODE ISLAND

DESIGN FOR A CHAIN FOR PERSONAL ADORNMENT

Application filed August 24, 1932. Serial No. 44,680. Term of patent 3½ years.

To all whom it may concern:

Be it known that I, KARL FASSNACHT, a citizen of the United States of America, residing in Providence, county of Providence, State of Rhode Island, have invented a new, original, and ornamental Design for a Chain for Personal Adornment, of which the following is a specification, reference being had to the accompanying drawing, forming a part thereof.

Fig. 1 is a top plan view, and

Fig. 2 is a side elevation of the chain for personal adornment showing my new design.

I claim:

The ornamental design for a chain for personal adornment, substantially as shown.

KARL FASSNACHT.
